DESIGN FOR A MECHANICAL LUBRICATOR

Bengt E. Folke, Mamaroneck, and Ralph H. Shepard, New York, N. Y., assignors to Nathan Manufacturing Company, New York, N. Y., a corporation of New York

Application May 1, 1945, Serial No. 119,329

Term of patent 14 years

(Cl. D78—1)

To all whom it may concern:

Be it known that we, Bengt E. Folke, a citizen of the United States and a resident of the village of Mamaroneck, in Westchester County and State of New York, and Ralph H. Shepard, a citizen of the United States and a resident of the city of New York, in New York County and State of New York, have invented a new, original, and ornamental Design for Mechanical Lubricators, of which the following is a specification, reference being had to the accompanying drawing, forming a part thereof.

In the drawing,

Fig. 1 is a plan view of a mechanical lubricator embodying our new design;

Fig. 2 is an end elevational view of the same, viewed from the right end;

Fig. 3 is an end elevational view of the same, viewed from the left end; and

Fig. 4 is a front elevational view of the same.

We claim:

The ornamental design for a mechanical lubricator, substantially as shown.

BENGTE FOLKE.
RALPH H. SHEPARD.
